ATTORNEY.

UNITED STATES PATENT OFFICE.

HUBERT HINDS, OF SPRINGFIELD, ILLINOIS.

CIRCUIT BREAKER.

Application filed October 31, 1925. Serial No. 66,001.

This invention relates to a class of devices commonly known as timers or commutators adapted to be used in connection with the ignition system of internal combustion engines and the like.

One of the purposes of this invention is to provide a circuit breaker for internal combustion engines which will be adapted to more successfully maintain a substantial and constant contact between the timer brushes or contact points and the moving rotor with which they are adapted to operate in serving as a circuit breaker.

The particular object of my invention is to provide an arrangement whereby the rotor in a circuit breaker may be formed into a plurality of segments formed in opposite angular pairs against the circumference on which the timer brushes may successfully maintain a substantial contact continuously over the same kind of metallic surface and not have to be constantly rubbing over first metal segment and then an insulating segment to break the circuit.

A further object of my invention is to provide a circuit breaker whose contact brushes may be adjustable so as to vary the length of time during which the ignition circuit is broken.

A further object of my invention is to provide a mount for the contact brushes that will constantly provide substantial springy resilient pressure against the brush in such a way as will enable the brush points to more successfully maintain steady contact with all points on the periphery of the rotor regardless of the speed of the rotor.

I attain the objects of my invention above mentioned, by the device described in detail in the annexed specifications, recited in the claims and illustrated in the accompanying drawings; in which like reference numerals will refer to like parts in the several figures:

Referring to the figures, Figure 1 is a top view of the circuit breaker of my invention shown with the distributor cap removed.

Fig. 2 is a vertical section $m-n$ of the circuit breaker of my invention.

Fig. 3 is a perspective of the brush holder used in this circuit breaker.

Fig. 4 is a cross section showing the method of mounting the brush on the brush holder.

Fig. 5 is an adjustable fulcrum mounting for the brush holder.

Fig. 6 is a perspective of T bolt used for

holding the brush holder in substantial operative position.

Fig. 7 is an end view of a rotor for the circuit breaker of my invention, showing how a rotor of six segments would be used.

Referring now to the details of the construction and the normal operation of the device of my invention, a rotor shown in Fig. 1 is rotatably mounted within the casting —28— and held into operative position by a nut-washer —6—. This rotor is provided with oppositely disposed segments —1— and —2— connected by wire and mounted in the insulation —5— of the rotor. Another pair of insulation segments —3— and —4— is likewise mounted in the rotor and connected by wire.

It will be seen that opposite bars of segments are connected by wire while adjacent segments are spaced apart and held thus in space relation therein by sheets of mica or other insulating material.

By arranging the segments on the rotor in this position it will be seen that when the brushes rub over the surfaces of the segment they do not need to come in contact with any insulation material in breaking the circuit.

Another important purpose of this circuit breaker is accomplished by the manner in which the brushes are mounted. It is desired to mount the brushes in such a way that the brush will closely follow the surface of the rotor segments at various speeds of the rotor without missing any surface by jumping. To accomplish this purpose, brushes —7— and —10— are mounted in a corresponding pair of detachable clamps —8— and —9— respectively. These brushes are clamped to the loose ends of a pair of leaf springs —11— and —12—. Spring —11— is adjustably mounted within the casting —28— upon an adjustable fulcrum —13— and held into operative position by T bolt —15— and thus secured by nut —21— which is adapted to force the draw bar —31— of T bolt —15— to pull outwardly against the forks —32— of leaf spring —11— thus pivotally urging brush —7— against the rotor segments.

Spring —11— is provided with a kink —33— adapted to snugly fit over the end of fulcrum lug —13— and it will be seen that by having brush —7— so mounted on such a spring that the result will be a tendency for the brush to follow the surface of the rotor

segments very closely even if they do happen to become worn in places.

It will be seen that by adjusting nut —21— to a tighter position on the thread that brush —7— is made to press more firmly against the rotor segments.

Fulcrum —13— is adjusted by loosening screw —22— slightly which screws into the fulcrum —13— and is slidably adjustable 10 within a slot of the casing —28—.

Spring —12— is pivotally mounted on lug —14— and made adjustable only by tightening nut —20— causing T bolt —16— to pull against forks —18— the result of which adjustment is to press brush —10— more firmly against the rotor segment.

It will be seen in Fig. 1 that brushes —7— and —10— are adapted to be normally positioned in a circumferential space relation of 20 somewhat less than 180 degrees.

By having brush —11— circumferentially adjustable within the casing —28— it will be seen that the period of time during which the circuit may be broken may be varied 25 within the limits of the adjustment.

An aperture —19— in the casing —28— is provided as means of access to the interior of the casing.

The ignition circuit in passing through 30 the circuit breaker enters through wire —30—, brush —10— passes through the rotor segments where the circuit is periodically broken by the turning of the rotor and is grounded by passing out through brush —7—, spring —11— through the casing and is grounded to motor or the frame of the car.

Fig. 7 shows how opposite segments are 40 connected by wire where for instance wire —26— connects segment —27— with the opposite segment —27'—. This view also shows how a plurality of segments may be moulded into the proper position in a suitable disk of insulation material —25—.

To those skilled in the art of automobile mechanics it will be evident that certain minor changes may be made in the structural details pertaining to the mounting of the brushes or the mounting of the segments in the rotor, but the preferred arrangement 45 50 is shown in Fig. 1.

In Fig. 4 it is shown the way in which brush —10— is insulated from the brush holder —12—.

Having thus described the nature of my 55 invention, what I claim is:

1. A circuit breaker of the character described comprising a rotor member having oppositely disposed metallic segments electrically connected molded within a circular 60 disc of insulation material; said oppositely disposed connected segments insulatably spaced from adjacent segments of like kind in the disc also electrically connected; a pair of contact brushes mounted within a casing 65 secured to the end of corresponding leaf springs adapted to substantially and resiliently urge said brushes into contact with the segments of a disc; said springs supporting said brushes adjustably mounted within a casing so as to provide variation in the circumferential space relation between said 70 brushes.

2. A circuit breaker comprising in co-operative combination, a plurality of oppositely disposed angular segments molded in a disc of insulation material and electrically connected; said segments closely spaced from and insulated from adjacent segments in the disc; adjustable contact brushes for 80 the circuit breaker mounted on pivoted leaf springs adapted to be circumferentially adjusted so as to provide variation in the circumferential space relation between contact 85 brushes mounted in the casing.

In witness whereof I hereunto set my hand this 1st day of August, A. D. 1925.

HUBERT HINDS.
